(57) **CLAIM**

The ornamental design for a descaler cleaner with short nozzle head and ramped body fins as shown and described.

DESCRIPTION

This application is related to U.S. application Ser. No. 29/883,329, titled "Universal Cleaner With Nozzle Head", filed Jan. 26, 2023, the entire disclosure of which is incorporated herein by reference for all purposes.

This application is related to U.S. application Ser. No. 29/883,330, titled "Universal Cleaner With Nozzle Head and Ramped Body Fins", filed Jan. 26, 2023, the entire disclosure of which is incorporated herein by reference for all purposes.

This application is related to U.S. application Ser. No. 29/883,331, titled "Descaler Cleaner With Narrow Nozzle Head", filed Jan. 26, 2023, the entire disclosure of which is incorporated herein by reference for all purposes.

This application is related to U.S. application Ser. No. 29/883,332, titled "Universal Cleaner With Short Nozzle Head", filed Jan. 26, 2023, the entire disclosure of which is incorporated herein by reference for all purposes.

This application is related to U.S. application Ser. No. 29/883,334, titled "Descaler Cleaner With Large Nozzle Head", filed Jan. 26, 2023, the entire disclosure of which is incorporated herein by reference for all purposes.

This application is related to U.S. application Ser. No. 29/883,335, titled "Descaler Cleaner With Smooth Body and Forward Nozzle Head", filed Jan. 26, 2023, the entire disclosure of which is incorporated herein by reference for all purposes.

FIG. 1 is a front perspective view of a descaler cleaner with short nozzle head and ramped body fins;

FIG. 2 is a rear perspective view of the descaler cleaner with short nozzle head and ramped body fins;

FIG. 3 is a front elevation view of the descaler cleaner with short nozzle head and ramped body fins;

FIG. 4 is a rear elevation view of the descaler cleaner with short nozzle head and ramped body fins;

FIG. 5 is right side view of the descaler cleaner with short nozzle head and ramped body fins;

FIG. 6 is a left side view of the descaler cleaner with short nozzle head and ramped body fins;

(Continued)

FIG. 7 is a top view of the descaler cleaner with short nozzle head and ramped body fins; and,

FIG. 8 is a bottom view of the descaler cleaner with short nozzle head and ramped body fins.

The various components shown in broken line illustrations are shown in broken lines for environmental illustrative purposes only and form no part of the claimed design.
